TREATING-MATERIAL INJECTION ATTACHMENT FOR COKE-IGNITING DEVICES

Donald Earl Mason, Greensboro, N. C.

Application August 4, 1948, Serial No. 42,406

5 Claims. (Cl. 302—25)

1

This invention relates to portable fuel igniting devices suitable for starting fires in the cupola furnaces of metal foundries, as described and claimed in my copending United States application, Serial No. 786,744, filed November 12, 1947, now Patent 2,492,705, issued Dec. 27, 1949, and it relates more particularly to special attachments for such devices.

An important object of my invention is to provide an attachment for fuel igniting devices for injecting powdered treating materials into the furnace charge to modify the physical or chemical characteristics of the metal being produced.

Another object of my invention is to provide a treating-material injection attachment of simplified construction which is capable of replacing the electrode structure of fuel igniting devices and which, when out of service and removed from the device, occupies very little space.

Still another object of my invention is to provide a treating-material injection attachment of the above character which is so constructed and arranged that the air flowing through the fuel igniting device causes the attachment to vibrate and hence induce pulsations into the air flow which overcome any tendency of the powdered treating-material to clog the passages of the device.

The invention will be more clearly understood from the following detailed description of a preferred form of the invention, reference being had to the annexed drawing in which:

Figure 1 is a longitudinal cross-sectional view of a coke-igniting gun;

Figure 2 is an end view of the gun of Figure 1 taken on the line 2—2 of Figure 1;

Figure 3 is a side view, partly cross-sectional, of the spinner for imparting vibration to the electrode during operation of the gun;

Figure 4 is a plan view of the butt end of the gun showing a fitting including the air lines for supplying air to the gun coupled thereto; and

Figure 5 is a longitudinal cross-sectional view of the gun corresponding to Figure 1 but having the central electrode and associated structure replaced by a treating-material injection attachment.

The fuel igniting device shown in the drawing comprises a cast iron gun 1 made up of a butt section 1a and a barrel section 1b threadedly secured together in substantial alignment. Both gun sections are hollow and generally cylindrical in shape, the butt section being of larger diameter than the barrel section, and the two diameters merging through a short tapered transi-

tion portion 1c. The butt section is formed with two longitudinal and parallel extending passageways 2 and 3. The passageway 2 is located in alignment with the bore of the barrel and is closed by a plug 4 screwed into the end of this opening, while the air duct or passageway 3 constitutes a branch which communicates with the passageway 2 and is closed at the same end as passageway 2 by a wall 3a.

Extending axially through the barrel and passageway 2 is a welding rod 5 which forms the electrode of the gun, and this welding rod projects a short distance beyond the open end of the barrel and also passes through a recess in the plug 4 at the opposite closed end of the gun. A tube of insulating material 6, such as hard fiber, encircles and supports the welding rod throughout the major portion of its length but leaves the tip of the rod exposed for a short distance inwardly from the open end of the gun. The welding rod at the closed end of the gun is suitably connected to a wire or cable 7 which forms one side of an electrical circuit by which current is supplied to the electrode, the other side of the circuit being represented by the metal gun 1 which is connected to the ground via a wire or cable 8.

A flexible air hose 9 leading from a source of air pressure (not shown) is arranged so as to deliver combustion air through an opening in the wall 3a at the closed end of passageway 3 which air flows along this air duct into the passageway 2 and thence through the barrel 1b of the gun in the space intermediate the welding rod and the wall of the barrel, ultimately escaping through the open or muzzle end of the barrel.

In order to allow powdered coke, or other highly inflammable material to be introduced into the air stream, a pocket 10 is provided on the gun adjacent its closed end, a hole being provided in the bottom of this pocket which communicates with the passageway 3. Inflammable material supplied to the pocket 10 is siphoned through the hole in its bottom to uniformly feed such material to the air stream.

The passageway 2 adjacent its plugged end is enlarged to form a chamber 11 and in this chamber a spinner 12 is rotatably mounted on the hard fiber tube 6 enclosing the welding rod and is held against longitudinal displacement by snap rings or other means embracing the tube. The spinner is provided with circumferentially spaced cups 12' against which is directed a jet of air from the nozzle end 13 of a tube leading outside of the gun and adapted to be connected to

a source of air pressure. The spinner is unbalanced by a small blob of metal 14 deposited off-center of its axis of rotation so that when the spinner rotates it imparts vibration to the welding rod. The air jet, and hence the rate of vibration, may be controlled by regulating the supply of air to the nozzle 13. The tube 6 is divided into two sections and held together by a flexible sleeve 15 which allows the welding rod to vibrate about this joint.

In the use of the fuel igniting device just described, the muzzle end of the gun, without the electrode, is passed through the brest or a tuyère of the cupola furnace and buried in a bed of small-lump coke C around and over which a charge of coke of normal size is deposited. The welding rod 5 is inserted into the tube 6 from the butt end of the gun and shoved along the tube to a point adjacent the end of the tube near the open end of the gun, after which a switch, suitably provided, is closed to allow current to flow to the welding rod. Simultaneously air is admitted to the air duct 3 by the opening of a suitable valve, from the air hose 9, and air is also admitted to the nozzle 13 to drive the spinner 12. Continued movement of the welding rod into contact with the coke causes an electric arc to be struck between the projecting end of the welding rod and the coke, the coke being grounded through the medium of the metal barrel of the gun. At the same time, ground coke placed in the pocket 10 is siphoned into the air stream and upon reaching the arc intensifies the burning of the coke. The coke is kept loose and agitated by the vibration induced in the welding rod by rotation of the spinner 12.

The air issuing from the muzzle of the gun produces a blast in the vicinity of the arc and at the point of burning of the coke. As a consequence, the combustion zone expands rapidly. The electrical current to the electrode and the air supply to the spinner are now cut off and the gun is allowed to remain in the bed of coke and continue to supply an air blast to accelerate the burning of the coke.

The air passing through the barrel of the gun will maintain the fiber tube 6 and the gun cool. The welding rods used in my gun may be those that are supplied for use in conventional welding equipment, several welding rods being secured end-to-end, and while such welding rods will be consumed at a fairly rapid rate during the operation of the gun, their cost is comparatively cheap and they are readily procurable on the market. A new welding rod 5 may be replaced by another in the tube 6 as it is consumed. The gun may be made in sufficiently small size and weight to permit it being readily carried from place to place, and it is of such a relatively simple construction as to practically insure it against getting out of working order.

The coke igniting gun just described corresponds in all essential respects to the apparatus described and claimed in my copending application above-mentioned. The present invention is concerned with a special attachment for use with the gun after the fire has been started in the cupola intended for introducing powdered treating materials, such as powdered carbon, graphite, alloying agents, etc., into the furnace charge in suspension in a large volume of air, so as to raise the carbon content of the iron, or, in the case of other treating agents, to modify the properties of the metal being melted in the furnace.

To accomplish the foregoing object, the plug 4 is removed from the gun by unscrewing, and the electrode 5, with its fibre insulating tube 6, and the spinner 12 are removed as a unit axially 5 through the open butt end of the gun. In place of these removed parts, an attachment is inserted so that the same gun may function as an injector.

The injection attachment comprises a long, 10 cylindrical, vibratory tube 16 made of metal which extends through the passageway 2 and throughout a portion of the length of the barrel section of the gun, terminating a substantial distance inwardly from the muzzle end of the barrel, as shown in Figure 5. The vibratory tube is 15 of such a diameter relative to the bore of the gun as to provide ample clearance for the unrestricted flow of air lengthwise through the space between the tube and the barrel.

20 The inner end of the vibratory tube 16 (that is, the end of the tube nearest the butt end of the gun) is mounted in a rubber sleeve 17 which forms a flexible coupling with a nipple 18 projecting axially from the inner face of a plug 19. The 25 plug 19 is generally similar to the plug 4, being threaded upon its circumference so that it may be screwed into the butt end of the gun to close the passageway 2. This plug is hollow and is internally threaded adjacent its outer end to 30 permit coupling to a hose 20 through which powdered material under pressure can be delivered to and through the vibratory tube, if necessary, to supply more material than can be siphoned from the pocket 10.

35 The discharge end of the vibratory tube is slightly flared, as indicated at 21, and the outside of this tube is covered by a layer of rubber 22 to protect the tube against the abrasive action of the siphoned material.

40 A piping arrangement for supplying air to the gun when the latter is operating either as a coke igniter or as an injection device is illustrated in Figure 4. The air hose 9 is coupled to a distributor pipe 23 which has a main branch 24 leading to and threaded within the end wall 3a 45 of the air duct 3 and a secondary branch 25 connected to the spinner-operating tube 13. A hand valve 26 controls the flow of air in the main branch 24 and similarly a hand valve 27 regulates the air flow in the secondary branch 50 25. A short pipe section 28, slightly closed at its discharge end to give it a nozzle effect, screws into the outlet end of branch pipe 24 to increase the suction through pocket 10.

55 The outer or muzzle end of the gun may be provided with a renewable tip 28 screwed into the barrel 1b.

In the operation of the device, after the fire in the cupola has been started in the manner described above, the air supply is cut off and the 60 gun is withdrawn. The plug 4 with its electrode assembly is removed endwise from the gun, as before described, and the plug 19 carrying the vibratory tube 16 is inserted in its place.

The muzzle end of the gun is now inserted 65 through one of the tuyères of the cupola into the wind box surrounding the cupola with its muzzle end terminating short of the inside circumference of the cupola. In this way advantage is taken of the air blast through the tuyère to intensify the siphoning action of the gun. During the operation of the gun as an injector, the electric current, of course, is cut off and the device operates exclusively by air.

In order to alter the composition of the furnace charge and hence to modify the charac-

teristics of the metal being produced, pulverized material is siphoned into the air stream flowing through the air duct 3 by feeding such materials into the pocket 10, just as powdered fuel was earlier fed into this pocket when the gun was used for starting the fire in the coke bed. For example, if an iron of high carbon content is desired, powdered carbonaceous material, such as graphite, is introduced into the pocket 10. This creates an atmosphere of high carbon concentration in the melting zone of the furnace with consequent absorption by the metal being melted. In the same way, other treating agents, such, for example, as forrosilicon, manganese and other alloys in powdered or granulated form may be injected into the furnace charge to impart the desired properties to the metal. Additional material may also be introduced into the gun from hose 20, if desired, as before mentioned.

During the use of the gun as an injector, the air discharged from nozzle 13 strikes the vibratory tube 16 and, by reason of the flexible connection 17, forces this tube laterally and then in its continued forward flow strikes the flared end 21 of the vibratory tube 16 urging the tube back again. Thus, the repetition of these actions causes the tube to rapidly oscillate about its rubber sleeve connection 17. This constant vibration of the tube induces pulsations into the air stream and these pulsations serve to prevent the powdered material from clogging the discharge outlet from the pocket 10 or the bore of the gun. Thus, the siphoning action of the powdered material into the air stream continues uninterrupted while the gun is in service. The powdered treating-material may be fed into the pocket 10 either manually or from a supply bin (not shown) adapted to be placed in communication with the pocket.

When the gun is operating as an injector using powdered material of a floury consistency, such as has a tendency to clog the passages of the gun, the valve 27 normally will be open to allow air to feed through the nozzle 13 for actuating the vibratory tube 16 and the valve 26 will remain closed. However, when material of coarser particle size is to be injected, the valve 27 may be closed and the valve 26 opened to admit air into and through the passageway 3, no need for the vibratory action of the tube 16 existing under such conditions.

The construction of the injector is such that the plug 19 and the vibratory tube 16 can be removed as a unit from the gun even while full air pressure is maintained through the gun from the air valve 26. This follows from the fact that the air flowing through passageway 3 exerts a forward pressure (that is, in the direction of the gun muzzle) rather than a backward pressure. Therefore, should vibratory tube 16 become clogged with material during operation this tube may be removed from the gun without the necessity of shutting off the air supply and without interrupting the flow of material from pocket 10.

From the foregoing description it will be apparent that the injection attachment is of relatively simple and efficient construction and capable of being quickly assembled with the coke-igniting gun forming the subject of my copending application, thus permitting the same gun to fulfill two different and important functions in cupola furnace operation—first, to start the fire in the cupola and, second, to modify the physical or chemical characteristics of the metal produced therein.

While a preferred specific embodiment of the invention has been set forth, it is to be understood that the invention is not to be limited to the exact construction illustrated and described but that various modifications of these details may be made within the purview of the appended claims.

I claim:

1. A portable treating-material injection device for furnaces comprising an elongated, tubular barrel open at its outer end and closed at its inner end, a vibratory tube extending lengthwise within said barrel and terminating short of the outer end of the barrel, a flexible coupling supporting said tube in spaced relation to the barrel and affording limited lateral movement for the outer end of the tube, means for connecting said barrel to a source of air pressure for introducing powdered materials into the barrel and air-operated means upon said tube for imparting vibration to the tube.
2. A portable treating-material injection device for furnaces comprising an elongated, tubular barrel open at its outer end and closed at its inner end, a vibratory tube extending lengthwise within said barrel and terminating short of the outer end of the barrel, a flexible coupling supporting said tube in spaced relation to the barrel and affording limited lateral movement for the outer end of the tube, means for connecting said barrel to a source of air pressure, means for introducing powdered materials into the barrel and an outwardly flared portion upon said tube adjacent its outer end for imparting vibration to the tube.
3. A portable treating-material injection device for furnaces comprising an elongated, tubular barrel open at its outer end, a plug closing the inner end of the barrel, a vibratory tube extending lengthwise within said barrel, a flexible coupling connecting the inner end of the tube to said plug and affording limited lateral movement for the outer end of the tube, a nozzle adapted to be connected to a source of air pressure for directing a stream of air against the tube, means for introducing powdered materials into the air flowing through the barrel and projecting means upon the tube for intercepting the flow of air through the barrel.
4. A portable treating-material injection device for furnaces comprising an elongated tubular barrel open at its outer end, a plug closing the inner end of the barrel, a vibratory tube extending lengthwise within said barrel, a flexible coupling connecting the inner end of the tube to said plug and affording limited lateral movement for the outer end of the tube, a nozzle adapted to be connected to a source of air pressure for directing a stream of air against the tube, projecting means upon the tube for intercepting the flow of air through the barrel, an air duct communicating with the barrel at a point intermediate the length of the barrel and an inlet for powdered materials communicating with the air duct.
5. A portable treating-material injection device for furnaces comprising an elongated tubular barrel open at its outer end, a plug closing the inner end of the barrel, a vibratory tube extending lengthwise within said barrel, a flexible coupling connecting the inner end of the tube to said plug and affording limited lateral movement for the outer end of the tube, a nozzle adapted to

be connected to a source of air pressure for directing a stream of air against the tube, an outwardly flared portion upon the tube adjacent its end for intercepting the flow of air through the barrel, an air duct extending approximately parallel to the barrel at a point intermediate the length of the barrel, and a pocket for holding powdered materials communicating with the air duct.

DONALD EARL MASON. 10.
